UNITED STATES PATENT OFFICE.

ISAIAH H. FARNHAM, OF MALDEN, ASSIGNOR TO THE NEW ENGLAND TELEPHONE AND TELEGRAPH COMPANY, OF BOSTON, MASSACHUSETTS.

ELECTRIC SWITCH-BOARD.

SPECIFICATION forming part of Letters Patent No. 394,964, dated December 25, 1888.

Application filed September 8, 1888. Serial No. 284,912. (No model.)

To all whom it may concern:

Be it known that I, ISAIAH H. FARNHAM, residing at Malden, in the county of Middlesex and State of Massachusetts, have invented 5 certain Improvements in Electrical Switch-Boards, of which the following is a specification.

This invention relates to electrical switch-boards, and more particularly to means for 10 protecting their spring-jacks and spring-jack contacts from dust and lint or other obstructions which have a tendency to accumulate within the crevices or operating-apertures of such appliances and which interferes with 15 their proper and successful operation.

It comprises the application to any form of switch-board of means for causing a continuous or periodic flow of air outwardly through the several spring-jacks thereof, and since 20 the spring-jacks of horizontal switch-boards are (inasmuch as they are vertically mounted with their orifice upward) peculiarly liable to be affected by dust and fibrous accumulations due to the attrition of flexible cords, clothing, 25 and other causes it especially comprises the application of such means to switch-boards of such character.

It contemplates also the casing up of the rear or lower side of the switch-board in an 30 approximately air-tight manner, so that a comparatively feeble air-pressure may be altogether exerted in the proper direction—viz., outwardly through the spring-jacks; and it consists, furthermore, also in providing apparatus—such as a fan—driven by steam or 35 other power, a pipe carrying cold air rarefied in transit by proximity to a hot-air pipe, a steam-pipe or otherwise, or by pedal-operated bellows, also in heating the said air so rarefied by the same means, and, finally, in providing and combining with the said apparatus 40 for increasing the air-pressure behind the switch-board suitable cleansing devices through which the said air must pass on its 45 way to the switch-board, whereby all impurities may be arrested and prevented from passing into the switch-board casing.

The switch-boards employed in large telephone-exchanges must necessarily be of sufficient capacity to accommodate a very great 50 number of lines, and it has been found that

the best results are attained and that the greatest number can be operated in a single switch-board when each line passes through permanent spring-jack contacts and when the 55 connection between any two lines or between any one line and the central-station apparatus is effected by means of flexible conductors. Such switch-boards are therefore 60 now universally preferred to switch-boards of that class wherein permanent vertical and transverse conducting-bars adapted to be connected by metallic pins at their intersections are employed. Moreover, it is sometimes found 65 advantageous to construct horizontal face switch-boards such as indicated in the drawings, because by employing these more operators are enabled to reach the same number of spring-jacks, and therefore when multiple 70 switch-boards are required a less frequent multiplication is necessary with the horizontal or flat board than with boards having as usual a vertical face, and consequently the flat board tends to material economy in construction. In both forms it has been found 75 that dust and detritus tend to accumulate within the spring-jacks, although the said tendency is obviously much more pronounced 80 and injurious in the horizontal form of switch-board than in the other. The presence of such extraneous matters seriously impairs 85 the efficiency of the contacts and sometimes interposes so high a resistance between the resting contacts as actually to open the main circuit.

In the drawings which illustrate and form a part of this specification, Figure 1 is a perspective view of a switch-board cased up round the rear part of the spring-jacks and combined in accordance with this invention 90 with means for increasing the air-pressure in the interior of such casing, and thus for producing a gentle circulation outwardly through the spring-jacks. Fig. 2 is a view of a cleansing-screen suitable for employment in connection with the apparatus. Fig. 3 is a vertical transverse cross-section of a horizontal switch-board, taken through a line of spring-jacks and showing the main air-pipe, also in cross-section. Fig. 4 is a detail of a modification indicating the formation of an air-current due to rarefaction by means of the prox-

imity of a steam-pipe. Fig. 5 shows an air-pipe in which the air is heated and rarefied by leading the pipe through a chimney-flue; and Fig. 6 shows a switch-board having its 5 air-currents established, when desired, by means of pedally-operated bellows under control of the operator.

In Figs. 1, 3, and 6, *a* is a switch-board of that class which may be termed "horizontal" 10 switch-boards. The said switch-board is or may be mounted upon the floor of the operating-room, as shown, or upon a raised platform adapted for the purpose, and the under or back part of the board is cased up moderately 15 air-tight, so that all of the rear ends of the plug-sockets or spring-jacks open into an inclosed space, as clearly indicated in Fig. 3. The rear wall of this air-tight casing may be close to the floor, or, if desired, at a higher 20 point from side wall to side wall. This is not material.

The several series of spring-jacks *j* may, as usual be constructed in independent sections or panels, as in Fig. 1, where four of such 25 spring-jack-containing panels are shown placed side by side at the right-hand end of the switch-board, the other panel places, 3, being in the drawings unfilled. The first side space, 2, may be filled up with connecting-plugs *q*, each constituting the end of a flexible conductor, and each capable of being raised in a manner well understood and inserted in any of the spring-jacks for the purpose of making or changing an electrical connection. Still nearer the edge of the switch-board face, upon the longitudinal space 1, and this at both sides, may be ranged the calling 35 keys or buttons *k*.

The call-receiving annunciators *z* may also 40 be arranged in panel-sections 4 on both sides of a raised box, *B*, which extends longitudinally from one end to the other of the switch-board, being supported thereover upon hollow pillars or columns 5, through which, or 45 otherwise, their connecting-wires may be led.

In order to keep dust and such matters entirely out and to do this without any alteration or attachment to the jacks, I provide means for slightly raising the air-pressure 50 within the case or back of the switch-board, and this increase of pressure causes an outward circulation of air through the jacks or plug-sockets, and, in fact, through any opening, aperture, or crack which may be in or 55 about the board, as indicated by the arrows, Figs. 1 and 3. In Fig. 1 is shown suitable apparatus for accomplishing this. A fan-blast, *F*, driven, as indicated, by steam or other power, is conveniently placed in or near the switching- 60 room, or where desired, and supplies the required air-pressure and circulation by means of the pipes *p'* and *p*, the air passing through the pipe *p* being preferably forced through a cleansing-box, 6, in which any desired number 65 of screens or strainers, 7, may be placed for the purpose of preventing dust or objectionable matter from being carried into the

casing with the air. These screens, 7, may be made of such a construction that they can be easily introduced or withdrawn from the box 70 6, and the several slides will preferably be made with different grades of mesh, from fairly close cloth to wire-netting. This box 6 is placed intermediately between the fan and the switch-board, and the pipe *p*, after 75 leaving the said cleansing-box, passes to the switch-board, and, entering the inclosed space thereof, may be extended longitudinally therein, as shown in dotted lines in Fig. 1, and may be perforated at as many points as desired, 80 as indicated in cross-section in Fig. 3, for the distribution of the fresh-air supply.

The adoption of this invention will totally prevent the deposition of dust, because the air under a determinate pressure is constantly 85 in circulation, and because that circulation is with respect to the spring-jacks at all times outward.

Other apparatus may be substituted for the fan-blast without departing from the spirit of 90 my invention.

Referring, for example, to Fig. 4, the supply of air may be taken from the outside of the building by means of a pipe, *d*, extending through the wall *w*, the said pipe being provided at its mouth with a suitable strainer, *e*. The pipe *d* connects with or continues as the tube *b*, through which a steam, hot-air, or hot-water pipe, *s*, passes, this being mainly used for heating purposes. The inclosing draft-pipe *b* is of course sealed at the points *g* and *c*, where the steam-pipe enters and leaves it, and from the pipe *b* the pipe *p* to the switch-board is led. The pipe *p* may be, as with the former apparatus, led through the screen-box 105 6. In the adoption of this apparatus a circulation would be created by the rarefaction consequent upon the heating derived from the steam-pipe, and air would consequently 110 pass readily through and increase the pressure within the closed switch-board casing, relieving itself, of course, through the spring-jack, in the manner already described.

If desired, of course, the circulating air may be also in this way warmed on its way to the 115 board, and during the summer the air may by equally simple means be cooled. The air-pipe may, for example, be led through a trough in which ice may be placed, or into which water is caused to flow or drip over the said air-pipe; but in any case the air which is forced into the back of the switch-board for increasing the pressure should always be taken from out of doors, and will then greatly aid in giving good ventilation to the usually crowded room; or, 120 again, the induction-pipe *p* may on its way to the switch-board, as in Fig. 5, be led through the flue *f* of a chimney, *C*, through which the heated products of combustion are passing, and the rarefaction and consequent circulation may in this way be produced.

If none of the modes and apparatus which I have described be in any individual case convenient, recourse may be had, as shown in

Fig. 6, to a series of bellows to be actuated whenever desired by the foot of the operator. In the figure, *a* is the switch-board; *R*, a pair of bellows, of which as many as may be rendered necessary by the size of the switch-board may be provided. *p* is the main air-pipe, *g* the bellows-pedals projecting from the switch-casings, and *s* the pipe-nozzles projecting from the several pairs of bellows into the *e* casing.

It may not in every case be necessary that the pressure-producing or air-circulating apparatus shall at all times be in operation, since periodic operation, if of regular and frequent *o* occurrence, will meet the desired end.

I am well aware that dust-guards have heretofore been patented in connection with switch-boards; but, as will have been seen, I propose to attack the evil from another direction and *o* to keep the dust entirely out of the jacks, and that without complication in or addition to the construction of the said jacks.

Of course I am not restricted to any particular length of switch-board, and section after *o* section provided with means for circulating air through the spring-jacks outwardly can readily be added end to end.

I claim as my invention—

1. An electric switch-board having spring-jacks or plug-sockets on its face, and having an air-tight casing at its rear inclosing the rear end of the said jacks or sockets, combined, substantially as described, with means for increasing the air-pressure within the said *o* casing and for maintaining a circulation of air through the said spring-jacks in an outward direction, whereby the deposition of dust, lint, or other impurity within the spring-jacks may be prevented.

2. The combination, substantially as hereinbefore set forth, of a horizontal switch-board having vertically-mounted spring-jacks or plug-sockets, with orifices opening upwardly and provided with an air-tight casing *o* inclosing the rear openings of the said spring-jacks, and means, as indicated, for establishing a constant or periodic circulation of air through the spring-jacks, for the purpose of preventing the deposition and accumulation *o* of dust or detritus therein.

3. The combination, substantially as hereinbefore described, of an electric switch-board having plug-sockets or spring-jacks on its face, and having an approximately air-tight-back casing for the rear end of the said *o* jacks or sockets, with a fan-blast worked by suitable power and a pipe from the said fan to the air-tight casing of the said switch-board, whereby the air-pressure within the switch-board casing may be increased and *o* circulation through the spring-jacks in an outward direction maintained.

4. In combination with a switch-board having a horizontal operating-face, with its spring-jack orifices pointing upward, and provided *o* with an approximately air-tight casing at its rear side, within which the inner ends of its spring-jacks are inclosed, an air-pipe leading into the said inclosed chamber, and a fan-blast or its equivalent for forcing air under *o* suitable pressure through the said pipe into the said chamber, and thus to establish circulation outwardly through the spring-jacks, as and for the purposes described.

5. An electric switch-board having a flat *o* and horizontal operating-face and spring-jacks or plug-sockets vertically mounted therein, with their orifices open in an upward direction, the said switch-board being constructed with an approximately air-tight casing *o* inclosing the inner ends of the said spring-jacks, combined with an air-pipe leading from the open air into the said inclosed chamber, a fan or other pressure-producing device for forcing the air through said pipe into said *o* switch-board casing, and a cleansing-box fitted with strainers or screens to arrest and retain impurities included in said air-pipe between the said pressure-producing device and the switch-board chamber, substantially as *o* described, and for the purposes specified.

In testimony whereof I have signed my name to this specification, in the presence of two subscribing witnesses, this 28th day of August, 1888.

ISAIAH H. FARNHAM.
